UNITED STATES PATENT OFFICE.

RICHARD VARLEY, OF ENGLEWOOD, NEW JERSEY, ASSIGNOR TO THE AUTOCOIL COMPANY, A CORPORATION OF NEW JERSEY.

IGNITION SYSTEM FOR EXPLOSION-ENGINES.

No. 915,391.

Specification of Letters Patent. Patented March 16, 1909.

Application filed June 4, 1908. Serial No. 436,543.

To all whom it may concern:

Be it known that I, RICHARD VARLEY, a citizen of the United States, residing at Englewood, in the county of Bergen and State of New Jersey, have invented certain new and useful Improvements in Ignition Systems for Explosion-Engines, of which the following is a full, clear, and exact description.

10 This invention relates to ignition systems for explosion engines, and more particularly to an arrangement by which the duration of the primary circuit closure is varied with respect to the stroke of the engine.

15 The ordinary circuit controlling device for an ignition system is driven by the engine and closes the circuits of an induction coil, or, more generally, a plurality of induction coils at fixed intervals and for a predetermined duration or "dwell." The longer the period of circuit closure or dwell, the more certain the ignition becomes, but, on the other hand, a long circuit closure consumes an excessive battery current, and, in many 25 cases uselessly, since the engine ordinarily operates properly with very short current duration. Some means for regulation is desirable, especially as the controlling device is driven by the engine so that the primary dwell is less at high speeds than at low 30 speeds.

It is the principal object of my present invention to have the primary circuit closure or dwell controllable so as to be suited to the 35 conditions.

In my co-pending application, Serial No. 436,542 filed herewith, I have set forth a construction for effecting the above described purposes, which includes separate controllers, or banks of segments having a common 40 rotatable element and having the different series or banks of segments or contacts of different angular extents, which are adapted to be used in multiple or parallel circuits at 45 certain times. The present application covers another form of the broad invention, also making use of segments of different angular extents in different series or banks, which are, at certain times, connected in series 50 with one another and, at other times, used individually to change the primary "dwell." The present application is therefore distinguished from my co-pending application by the fact that in the present application the 55 primary "dwell" is always shortened by

connecting in a series circuit two segments or contacts of different angular extent, while, in said co-pending application, the primary "dwell" is lengthened by including two segments or contacts of different angular extent in a multiple circuit. The present invention more particularly consists in the features of construction and combination as hereinafter set forth and finally particularly pointed out in the appended claims. 60

In the drawing: Figure 1 is a diagrammatic view showing a circuit controller and ignition system embodying the principles of my invention. Fig. 2 is a vertical sectional view of the controller. Fig. 3 is a partial 71 sectional view on the line III—III of Fig. 2. Fig. 4 illustrates a still further modification.

In the form of the invention shown in Figs. 1, 2, and 3, there are provided a plurality of induction coils C' C² C³ C⁴. B designates the 75 battery or current source, and 1 denotes broadly a circuit controller adapted to close the primary circuits of the coils in a predetermined order and in such a manner that the duration of the primary circuit closure 80 or "dwell" can be varied. The controller 1 preferably includes a casing or housing 2 of insulating material, having an upper bank of segments 3 and a lower bank of segments formed by a single metallic ring 4 which is 85 cut away along spaced sections 5 at its interior surface. In this way there are presented a number of portions 6 of the ring, which form the equivalent of segments or contacts. The ring 4 is embedded or surrounded by insulating material, so that the contact portions 6 of the ring are alone exposed at the interior surface of the insulating housing 2. 8 designates the revolute element of the controller, which may be made 90 in any desired way, so as to prevent two separate arms in rotatable engaging relation with segments 3 and the contacts 6, respectively. For this purpose the separate arms are located in different planes corresponding 95 to the planes of said segments and contact ring. I prefer the construction shown, making use of a flier 9 fixed to the shaft 10 and having sets of arms 11 and 12, respectively carrying the spring pressed rollers 13 and 14. The roller 13 is adapted to engage the segments 3, while the roller 14 revolves in the path of the contacts 6. The rollers are preferably disposed on diametrically opposite sides of the shaft 10, so as to give a balanced 100 105 110

construction. The disposition of the various segments and contacts is such that the roller 13 passes onto a segment 3 at the same instant that the roller 14 passes onto a contact 6. The segments 3 are, however, of considerably greater angular extent than the contacts 6, so that the contact of the roller 13 is continued for a longer interval with its segment than the engagement of the roller 14 with its contact 6. With a controller of this construction, an arrangement of circuits may be adopted as shown in Fig. 1. l' , l^2 , l^3 , and l^4 designate connections from the various segments 3 to one primary terminal of the various induction coils, the other primary terminal of these coils being connected with the battery B, through a wire m . 16 designates a switch adapted to connect the other terminal of the battery to ground through contact 17 and wire n , or to the ring 4 through contact 18 and a terminal 19.

The operation is as follows: Assuming that the parts are in the relation shown in Fig. 1, the circuit of the primary of induction coil C^2 is just on the point of being completed as follows: battery B, wire m , primary coil C^2 , wire l^2 , segment 3, roller 13, through the flier to roller 14, contact 6 and ring 4, terminal 19, wire o , contact 18, switch arm 16, back to battery B. Since this circuit includes both of the rollers 13 and 14, it is evident that it can continue only as long as these rollers are engaging their respective segments or contacts. The circuit will, therefore, be terminated as soon as the roller 14 passes off of its short contact 6 of the ring 4. This circuit condition therefore corresponds to a short primary circuit closure or "dwell." If now the switch arm 16 is moved over onto contact 17, the primary circuit of coil C^2 will be closed during the entire interval that the roller 13 is passing across the segment 3, since the flier is grounded through its supporting shaft. The circuit is as follows: battery B, wire m , wire l^2 , segment 3, roller 13 to ground, wire n , contact 17, switch arm 16, back to battery B. The change in circuit conditions from a long to a short primary "dwell" and vice versa is, therefore, accomplished by a movement of the switch arm 16, but the change does not effect any variation in the instant when the primary circuits are initially closed for the various coils.

In Fig. 4 I have illustrated a construction of controller very similar to that of Fig. 1, except that, in place of roller 14, I make use of a spring-impelled plunger 25. In place of a ring 4, I make use of a ring 4' having slightly rounded contact points 6'. The plunger 25 is slightly depressed inward in passing these contacts and establishes a circuit connection therewith in a manner and for an interval similar to the engagement of the roller 14 with the contact 6 in Fig. 1. In all other

respects the operation and the circuit connections are exactly like those of Fig. 1.

What I claim is:

1. In an ignition system, an induction coil and a primary circuit controller therefor, including a plurality of rotating devices in different planes, contacts in the planes of different of said devices, the contacts of different devices having a different angular extent, and means for including the contacts of one, or the contacts of more than one of said planes in series, in said primary circuit, whereby the primary dwell is varied, the initial engagement of said contacts and devices being made simultaneously in the respective planes. 70

2. In an ignition system having a primary circuit, a pair of members adapted to have a continuous angular displacement with respect to one another, contacts carried by one of said members, and contact devices in different planes carried by the other of said members, the different contact devices respectively having an engagement of different angular extent with the said contacts, and means for completing said primary circuit through one of said devices, or more than one of said devices in series, whereby the primary dwell is varied, the initial engagement of said contacts and devices being made simultaneously 85 in the respective planes. 90

3. In an ignition system, an induction coil and a primary circuit controller therefor, including a plurality of rotating contact devices in different planes, sets of contacts of different angular extent in the paths of said contact devices, and a single switch for putting the contacts of one set, or the contacts of more than one set simultaneously in series in said primary circuit, whereby the primary 100 dwell is varied, the initial engagement of said contacts and devices being made simultaneously in the respective planes. 105

4. In an ignition system, an induction coil and a primary circuit controller therefor, including a plurality of rotating contact devices in different planes, sets of contacts of different angular extent in the paths of said contact devices, and means for including the contacts of only one set, or the contacts of more than one set simultaneously in series, in said primary circuit, whereby the primary 110 dwell is varied, the initial engagement of said contacts and devices being made simultaneously 115 in the respective planes.

5. In an ignition system, an induction coil and a primary circuit controller therefor, including a plurality of rotating devices in different planes, segments in the path of one of said devices, and a notched ring having contact portions in the path of the other of said contact devices, said segments and said contact portions of the ring having a different angular extent, and means whereby said segments alone, or said segments and said 125 130

ring in series, are included in said primary circuit, whereby the primary dwell is varied, the initial engagement of said contacts and devices being made simultaneously in the 5 respective planes.

6. In an ignition system, a pair of members adapted to have a continuous angular displacement with respect to one another in one direction, segments carried by one of 10 said members, a contact device carried by the other member to engage said segments, a notched metallic part having contact portions, a contact device in a different plane from the first engaging said notched metallic 15 part during the said angular displacement of

the members, means whereby said segments and their contact device alone, or said segments and both contact devices and said notched metallic part in series, are included in the primary circuits of said ignition system, 20 whereby the primary dwell is varied, the initial engagement of said contacts and devices being made simultaneously in the respective planes.

In witness whereof, I subscribe my signature, in the presence of two witnesses.

RICHARD VARLEY.
